Primary Examiner — Darcey E Gottschalk*Assistant Examiner* — Vanessa M. Pursley(74) *Attorney, Agent, or Firm* — Sheridan Ross P.C.(57) **CLAIM**

The ornamental design for a metallic dispensing lid, as shown and described.

DESCRIPTION

FIG. 1 is a top perspective view of a metallic dispensing lid; FIG. 2 is a bottom perspective view thereof;

FIG. 3 is a front elevation view thereof, the rear elevation view being substantially the same as the front elevation view;

FIG. 4 is a right side elevation view thereof, the left side elevation view being substantially the same as the right side elevation view;

FIG. 5 is a top plan view thereof;

FIG. 6 is a bottom plan view thereof; and,

FIG. 7 is a cross-sectional front elevation view thereof taken at the line 7-7 in FIG. 5.

In the drawings, the broken lines show portions of a metallic dispensing lid that form no part of the claim.
